LAMB DOCKING DEVICE

Michael J. Walczak, Casper, Wyo.

Application July 23, 1948, Serial No. 40,321

6 Claims. (Cl. 128—303.10)

1

This invention relates generally to knives and more particularly to a lamb docking device including a platform with a knife pivoted thereon and means to heat the knife when the knife is in one position.

A primary object of this invention is to provide a docking device suitable for docking the tails of lambs, the knife used in the device being heated prior to the actual cutting operation so that the wound is seared and no bleeding or infection is encountered.

Another object of this invention, of a general nature, is to provide means to facilitate generally the docking of considerable numbers of lambs, with a minimum number of men being required to carry out this operation.

Still another object of this invention is to provide a docking device which can be used in the field so that the lambs need not be driven or transported great distances to a docking station, this device being easily shifted so that the docking station itself can be moved to the most convenient portions of the sheep ranch, and in this regard it should also be noted that a canopy is provided to prevent the wind from interfering greatly with the heating of the knife.

Still another object of this invention is to provide a docking device in which the knife is held in heating position automatically, and in which adjustment is provided in tail-guiding means, whereby the device may be adjusted for use with lambs of slightly different ages.

And a last object to be mentioned specifically is to provide a device of this nature which is relatively inexpensive and practicable to manufacture, which is light to transport, which is extremely simple and convenient to use, and which will give generally efficient and durable service.

With these objects definitely in view, this invention resides in certain novel features of construction, combination and arrangement of elements and portions as will be hereinafter described in the specification, particularly pointed out in the appended claims, and illustrated in the accompanying drawings which form a material part of this application, and in which:

Figure 1 is a three-dimensional view of the assembled device;

Figure 2 is a top plan view of the device;

Figure 3 is a vertical sectional view, taken substantially upon the line 3—3 of Figure 1;

Figure 4 is a longitudinal vertical sectional view, taken substantially upon the line 4—4 of Figure 2;

Figure 5 is a side elevational view, of a modified form of this invention showing a different means for biasing an arm carrying the knife, a portion of the above mentioned canopy being broken away to show how the arm is pivoted on

2

a short upright standard within the canopy; and Figure 6 is a fragmentary horizontal sectional view, taken on the line 6—6 of Figure 5.

Similar characters of reference designate similar or identical elements and portions throughout the specification and throughout the several views in the drawings.

Referring now to the drawings in detail, the environment wherewith this invention is adapted to be used includes a support 10, which may be a table, bench or any other suitable structure to be found at the scene of operation.

The device per se includes a platform 12 which can very well be constructed of metal and this platform has depending end flanges 14 with attaching clamps 16 rigidly secured thereto, thumb screw portions of these clamps being indicated at 18.

A heater 20 which may conveniently take the form of an ordinary blow torch heater, is secured to the platform 12 by an attaching bracket 22 of any suitable character, the fuel and air mixer 24 of the heater having the inner end thereof extending within a canopy 26 of inverted U-shape. The canopy 26 is rigidly secured to the upper face of the platform 12 near one end thereof and one end of the canopy may be closed as indicated at 28.

A short upright standard 30 is rigidly secured as indicated at 32 on the surface of the platform 12 within the canopy 26, and this standard 30 is bifurcated, at least at the top thereof, as at 34, to facilitate the pivotal securement thereon of an arm 36, by means of a pivot pin 37. The free end 38 of the arm is guided by a vertically channeled upright standard 40 secured, as indicated at 42, to the other end of the platform 12, the closed upper end of the channeled upright acting as a stop for the end 38 of the arm 36 when the arm is pivoted upwardly.

A knife 44 is secured by a bolt 46 between a pair of flanges 48 on a tubular handle 50 which is telescopically arranged on the arm 36 to slide between a heating position with one end of the handle engaging the short standard 30 and a second position with the other end of the handle engaging a stop 52 longitudinally adjustably secured on the arm 36. The handle is perforated at a plurality of points 54 to allow air circulation within the tubular handle in order to dissipate heat from the portion of the handle remote from the knife 44. The knife 44 depends from the said flanges 48 adjacent said one end of the handle and it should be carefully noted that the knife is not rigidly held in these flanges since it is desired that the cutting edge of the knife may conform with the surface of a cutting block 56 of wood or other suitable material having a portion projecting upwardly through a recess in the platform 12 adjacent the knife 44 when the same

is in operative position, the block 56 being secured to the platform 12 by screws 58 or any other suitable fastening means. In other words, the knife 44 can rock slightly upon the bolt 46. The tubular handle 50 may have a hand grip 59 of wood or other heat insulating material.

A tail guide 60 including a plate member with upstanding diverging flanges 62 at one end and a downturned flange 64 at the other end, is transversely adjustably mounted on the platform 12 adjacent the cutting block 56, by means of angle guides 66 disposed laterally of the horizontal plate portion of the guide 60 and a headed adjusting screw 68. The screw 68 is threaded through a depending flange 70 on the underside of the platform 12 and this screw turns freely in the depending flange 64. A spring 72 is compressed between the flanges 64 and 70 to bias the tail guide in one direction.

In the form of this invention described above, the arm 36 is biased to pivot upwardly at the end 38, by means of a spring 74 secured between an attaching bracket 76 on the underside of the platform 12 and a downwardly turned portion 78 on the other end of the arm 36, the platform being slotted as at 80 to allow this portion 78 to reciprocate, all as will be clearly understood from an inspection of Figure 4. In the modification of this invention illustrated in Figures 5 and 6, the portion 78 of the arm 36 is deleted, and a spring 82 is compressed between the free end of a shortened arm 36' and the platform 12, the spring 82 being guided by a modified standard 40' which may take the form of a tube, the tube being vertically slotted to receive the arm 36'. The other portions of the invention are unmodified in this second type of arm and spring biasing construction.

The operation of this invention will be clearly understood from a consideration of the foregoing description of the mechanical details, taken in connection with the above recitation of the objects sought to be achieved by this invention. In recapitulation, it might be added that when docking lambs, the operator, by feeling on the inside of the tail, first locates the joint to be cut, which is about one and one-half inches from the body. The operator holds the lamb against the platform 12 with the tail in the tail guide 60, this guide being adjusted by means of the set screw 68 so that a correct length of stub will be left after the docking operation. Of course, when lambs in considerable numbers and of equal age are to be docked, the tail guide 60 is not adjusted for each individual lamb. With the heater 20 in operation, the knife 44 will be preheated and the handle 50 will be grasped by a second operator and the handle and knife will be shifted along the arm 36 into engagement with the stop 52 and the knife will then be lowered sharply upon the lamb's tail and against the cutting block 56. Since the knife is heated to a cherry red heat, the wound is seared and no bleeding or infection will be encountered. The spring 74 or 82 will return the arm to the position indicated in Figure 1 and the knife 44 will be again returned to be re-heated.

Obviously many minor variations may be made in this invention without departure from the spirit thereof. Accordingly, this invention should be limited only as determined by a proper interpretation of the terms and in the subjoined claims.

Having described the invention, what is claimed as new is:

1. A lamb docking device comprising a platform, a knife shiftably mounted on the platform, a heater adapted to heat the knife when the knife is in heating position, said knife being shiftable into an operative position to cut off a lamb's tail held between a portion of the platform and said knife in its operative position, said knife having a supporting arm pivoted on said platform and slidably supporting said knife.

2. A device according to claim 1, and including means to guide said arm.

3. A lamb docking device comprising a platform, a knife shiftably mounted on the platform, a heater adapted to heat the knife when the knife is in heating position, said knife being shiftable into an operative position to cut off a lamb's tail held between a portion of the platform and said knife in its operative position, said knife having a supporting arm pivoted on said platform and slidably supporting said knife, said knife having a handle telescopically associated with said arm.

4. A lamb docking device comprising a platform, a knife shiftably mounted on the platform, a heater adapted to heat the knife when the knife is in heating position, a block on said platform, said knife being shiftable into an operative position to cut off a lamb's tail held between said block and said knife in its operative position, said platform having a guide for a lamb's tail adjacent said block in its operative position, said guide comprising a plate having diverging flanges.

5. A lamb docking device comprising a platform, a knife shiftably mounted on the platform, a heater adapted to heat the knife when the knife is in heating position, said knife being shiftable into an operative position to cut off a lamb's tail held between a portion of the platform and said knife in its operative position, said platform having a guide for a lamb's tail adjacent the knife in its operative position, and said guide being adjustable transversely of the platform so that tails may be docked at different lengths.

6. A lamb docking device comprising a platform, an arm having a pivotal connection on said platform, a knife longitudinally slidably mounted on the arm, a heater adapted to heat the knife when the knife is in heating position, said knife being shiftable into an operative position to cut off a lamb's tail held between a portion of the platform and said knife in its operative position, said heater having a canopy to receive said knife in said heating position, said canopy also covering a portion of said arm adjacent to its said pivotal connection and means to bias said arm to pivot upwardly so that said knife will be biased by gravity to slide downwardly on the arm and to enter said canopy.
